UNITED STATES PATENT OFFICE

CONRAD CHIERIGHINO, OF NEW YORK, N. Y.

ALARM SYSTEM

Application filed December 21, 1927. Serial No. 241,625.

This invention relates to electric signalling apparatus and more particularly to an automatic alarm for operative connection with any telephone system and adapted to be installed in banks, offices, stores, hotels, apartments and other places which are liable to be burglarized and by the use of which apparatus police aid may be summoned, in the event of a "hold-up", or a serious argument which might be presumed to be liable to a conflict, without the offender being aware of the transmission of the call for assistance, the apparatus being likewise useful for the purpose of summoning aid in the event the one who is authorized to set the apparatus in operation should be seized with a severe heart attack or other serious illness liable to result in unconsciousness.

Another object of the invention is to provide an electric signalling apparatus of the class and for the purpose described which may be set in operation by the pressure of push button switches which may be located at various readily accessible points in the room in which the apparatus is installed and whereby, through an ingenious arrangement of such switches, so that they will be concealed from view of all except those having a knowledge of the presence of the apparatus, such switches may be actuated, as for example by foot or knee pressure, without the person or persons who are bent on committing a robbery, being apprised of the fact that a call for assistance has been made.

Another object of the invention is to provide an electric signalling apparatus of the type and for the purpose stated above which will operate automatically after a momentary pressure upon any one of the push button switches associated therewith, so that the one setting the apparatus in operation need not pay any attention to the apparatus after having once pressed the most conveniently accessible one of the several push button switches.

While the accompanying drawings and the description which is to follow, constitute a disclosure of the preferred embodiment of the invention, it will be understood that various

changes may be made within the scope of what is claimed.

In the accompanying drawings:

Figure 1 is a view partly in elevation and partly in section of the apparatus embodying the invention, the view illustrating, also, diagrammatically, the electric circuit;

Figure 2 is a top plan view of the apparatus, the closure for the casing being removed;

Figure 3 is a plan view, in detail, of a portion of the apparatus.

The greater portion of the apparatus embodying the invention is mounted in a casing 1 of rectangular form and which casing may be installed at any convenient point in the bank, office, store, or other place where the apparatus is to be employed, and the installation of the apparatus is to be in connection with the telephone system already installed in the office or the like.

The apparatus embodies a phonograph which is indicated in general by the numeral 2 and which may be of any of the compact types already upon the market, or may be specially constructed, as desired, the winding key for the motor of the phonograph being indicated by the numeral 3 and being rendered accessible by removal of the cover 4 for the casing 1. The phonograph 2 embodies the usual turn table 5 and the usual motor which is however not disclosed in the drawings inasmuch as it constitutes, in itself, no part of the present invention. The numeral 6 indicates a shaft which may be the spring shaft of the motor or a shaft driven therefrom, and this shaft extends through the wall of the body case of the phonograph and has fixed upon its outer end a gear 7 having two distinct peripheral portions one of which is toothed as indicated by the numeral 8 and the other of which is circular and smooth as indicated by the numeral 9, except that at a point in its circumference, it is formed with a notch indicated by the numeral 10. The numeral 11 indicates an armature which is pivoted at one end as at 12 within the case 1 and is provided at its other end with a pawl tooth 13 which is normally engaged in the notch 10. A tension spring 14 is fixed at its upper end within the

casing 1 and at its lower end is connected to the armature 11 and normally yieldably supports the armature in the position shown in Figure 1 of the drawings in which position its pawl tooth 13 engages in the notch 10, as stated above, the armature at this time being in spaced relation to the cores 15 of a pair of electromagnets 16 which are arranged preferably within the bottom of the casing and from which conductor wires 17 are led and connected one to a suitable source of current supply and the other to said source of supply and to one or more push button switches which are indicated by the numeral 18^a and which, as previously indicated, may be mounted at inconspicuous places about the room, office, or the like, in which the apparatus is installed, all of the switches being thus placed in circuit with the electromagnets 16. At this point it will be evident that the armature 11, being supported normally in the position illustrated in Figure 1, through the medium of the spring 14 and with its tooth 13 engaging the notch 10 of the gear 7, normally holds the gear against rotation so that the motor of the phonograph, is in turn held inactive. It will be understood however that upon actuation of any of the push button switches 18^a, the circuit will be closed through the electromagnets 16 thus attracting the armature 11 to the cores of the said magnets and disengaging the tooth 13 from the notch 10 of the gear 7 and releasing the gear and thus permitting the spring motor of the phonograph to operate.

The invention contemplates the automatic closing of a telephone circuit, upon rotation of the gear 7 at the time any one of the push button switches 18^a is actuated, and the transmission, over this telephone circuit, to the central operator, of a phonographic call for police aid, and with this in view, a telephonic transmitter 18 and the usual coil box 18' are arranged within the casing 1 opposite and slightly above the turn table 5 of the phonograph 2, the mouth piece of this transmitter unit being indicated by the numeral 19, and a bellows 20 being connected at one end therewith and at its other end to the flared end 2 of a sound wave conducting tube 22 which is freely slidably mounted in a bearing sleeve 23 at the outer end of a bracket arm 24 which is fixed upon one wall of the casing 1 and which is so positioned that the sound box or reproducing unit 25 which is supported at the end of the tube 22 may have its stylus 26 resting normally in engagement with a phonograph record 27 which is disposed upon the turn table 5, the tube 22 being initially slidably adjusted through the bearing sleeve 23 so that the stylus 26 of the reproducer 25 will engage in the outer end of the record groove in the phonographic record disk 27, this disk bearing a record of a series of requests for police assistance. The line wires

of the telephone circuit are indicated by the numeral 28 and are led to the relatively insulated portions 29 and 30 of a switch arm the section 29 of which is pivotally suspended as at 31 within the casing 1 in such position that when the said switch arm is swung to one of its positions of adjustment, it will bridge contacts 32 which are electrically connected by conductor wires 33 to the terminals of the transmitter 18, so that when the switch arm is, by means to be presently described, automatically actuated at the time the gear 7 is set in motion, and likewise at the time the turn table 5 is in motion, the circuit will be closed through the transmitted 18 and line wires 28 to signal the central operator of the telephone exchange who will hear the request for police assistance which is transmitted over the wires, from the phonograph record. As before explained, the record disk 27 bears a series of recorded appeals for police assistance, which, of course, may be worded in any manner desired, and, through means which will presently be described, the apparatus is designed to operate for a predetermined limited period of time when any one of the push button switches 18 is operated, so that, due to the provision upon the record disk 27 of a plurality of series of appeals for police assistance, the apparatus will be capable of operating a considerable number of times before there is any need for adjusting the reproducer 25 to bring the stylus 26 to the outer end of the record groove, and as the number of series of recorded requests will be in excess of any probable number of "hold-ups" or attempts at robbery, which might occur in a long period of years, the apparatus is, as will be readily understood, substantially of a permanent nature.

As illustrated in Figure 1 of the drawings, on ordinary telephone set 34, or any number of such sets, or a private exchange switch board may be employed beyond the apparatus housed in the casing 1, conductor wires 35 being led from the telephone set or sets or the switch board and led into the casing 1 and connected to contacts 36 which are arranged opposite and in spaced relation with respect to the contacts 32, the switch arm, comprising the members 29 and 30, being normally held in engagement with the said contacts 36 and automatically movable out of engagement with these contacts and into engagement with the contacts 32 by a system of gearing which will now be described.

The system of gearing, referred to above, includes a pinion 37 which is rotatably fixed upon a stub shaft 38 which may be in turn mounted upon the motor casing of the phonograph 2, and this pinion is in mesh with the teeth 8 of the gear 7, so that when the gear 7 is released for rotary movement and rotates, rotary movement will be imparted to the gear 37. A segmental pinion 39 is fixed

with respect to the pinion 37 and the teeth 40 of the segmental pinion extend for a portion only of the circumference of the pinion and are designed, under conditions to be presently explained, to mesh with rack teeth 41 upon a rack bar 42 which is slidably mounted in a suitable bearing 43 upon the side of the motor casing of the phonograph 2, the rack bar 42 being pivotally connected 10 at one end as at 44 to an insulating section 45 which constitutes a part of the switch arm and which is arranged between the sections 29 and 30 of said switch arm, the rack bar being likewise provided upon its under 15 side with another series of rack teeth indicated by the numeral 46 which are designed to be engaged by the teeth 47 of a segmental gear 48 at a predetermined period in the operation of the apparatus as a whole. In order 20 that the segmental gear 48 may be rotated in consonance with the gear 37 and segmental pinion 39, a bevel pinion 49 is mounted upon the shaft 38 and meshes with a similar pinion 50 fixed upon the relatively adjacent 25 end of a shaft 51 which is mounted in suitable bearings 52 and which shaft 51 is provided at its other end with a worm 53 meshing with a worm gear 54 upon the inner end of the shaft 55 upon which the segmental 30 pinion 48 is mounted.

In carrying out the invention, the various gears and pinions, and the rack bar 42, are so proportioned and arranged that, when the apparatus is idle and the stylus 26 of the reproducer 25 is in the outer end of the record groove in the phonograph record 27, the notch 10 of the section 9 of the gear 7 will be engaged by the tooth 13 of the armature 11. At this time the gear 37 and segmental pinion 39 will occupy approximately the position shown in Figure 1 of the drawings, in which position the teeth 40 of the pinion 39 are in mesh at one end of the series of teeth, with the teeth 38 of the rack bar 42. Likewise, at this 45 time, the teeth 47 of the segmental gear 48 are out of mesh with the teeth 46 of the rack bar 42 but in close proximity, at one end of the series, to said teeth 46. The gears 7, 37, and 48 will, in the operation of the apparatus, 50 upon retraction of the tooth 13 from engagement with the notch 10 of the section 9 of the gear 7, rotate in the directions indicated by the arrows on the several gears. It will therefore be understood, by reference to Figure 1, that when the electromagnets 16 are energized by a pressure upon any one of the push button switches 18 and a closing of the circuit through the magnets, the armature 11 will be attracted to the cores of the magnets, 55 and the tooth 13 will be retracted from engagement with the notch 10 of the section 9 of the gear 7, and, at this time, the gear 7 will be released and will be rotated in the clock-wise direction indicated by the arrow 60 in Figure 1 on said gear. As the gear 7 ro-

tates in this direction, it will impart rotary motion to the gear 37 in an anti-clock-wise direction as indicated by the arrow applied to said gear in Figure 1, and, as the segmental pinion 39 is fixed with respect to the gear 37, 70 the said pinion will at this time be rotated and the teeth 40 thereon will mesh with the teeth 38 of the rack bar 42 thus effecting a shifting movement of the rack bar longitudinally toward the left in Figure 1 of the 75 drawing to bring the portions 29 and 30 of the swinging lever into engagement with the contacts 32 thereby closing the circuit through the transmitter unit 18 and placing this transmitter in circuit with the central 80 operator's receiving 'phone set. It will be evident that simultaneously with this operation of the parts, the turn table 5 of the phonograph 2 will be set in operation and consequently the recorded appeals for police assistance which are carried by the record disk 27 will be reproduced by the reproducer 25 and transmitted over the line wires 28 to the central operator at the telephone exchange 85 whose duty it will be to notify police headquarters of the existing danger. The phonograph record will of course include, in the recorded call for assistance, the street and number of the building in which the apparatus is installed, so that the central exchange 90 operator will be enabled to either transmit the required information to police headquarters or, by the switchboard, place police headquarters directly in communication with the transmitter 18 of the apparatus. There are 95 a sufficient number of the teeth 40 of the segmental pinion 39 to insure of proper shifting of the rack bar 42 to effect movement of the switch lever to cause engagement of its portions 29 and 30 with the contacts 32 and 100 at this time the untoothed or smooth portion of the pinion will merely ride past the teeth 41 of the rack bar 42. Likewise, at this time, the smooth or untoothed portion of the segmental gear 48 is riding past the rack teeth 105 46, due to the rotation of the said gear 48 in the direction indicated by the arrow, and the intermediate gearing comprising the bevel pinions 49 and 50 and the worm 53 and worm gear 54 is so arranged and proportioned 110 that a period of approximately two minutes will be required for the gear 48 to rotate substantially a complete revolution, after which period of time the teeth 47 of said gear will mesh with the teeth 46 of the rack bar 115 42 and thus effect shifting of the rack bar 42 to its original position in which position the portions 29 and 30 of the switch arm will be brought into engagement with the contacts 36 and the circuit through the transmitter 18 and line wires 28 will be broken. In the elapsed period of time referred to above, and due to the relative proportioning of the component operating parts of the 120 apparatus, one series of recorded requests 125 130

for police assistance upon the phonograph record 27 will have passed the stylus 26, so that, during this period, repeated calls for assistance will be transmitted by the transmitter 18, over the line wires 28, to the telephone exchange to be received by the operator or, through a connection of the transmitting circuit of the apparatus with police headquarters, by the officer in charge.

10 It will be understood that the bellows connection 20 between the mouth piece 19 of the transmitter 18 and the flared end 21 of the sound wave conducting tube 22, permits of travel of the stylus 26 in the groove of the record disk 27.

15 It will also be understood from the foregoing description that when any one of the push button switches 18^a is actuated and the gear 7 is set in motion and the switch is then relieved of pressure, this will not in any way interfere with continued operation of the apparatus for the reason that while the spring 14 lifts the armature 11 away from the cores of the electromagnets 16, the tooth 13 of the said armature will engage against the smooth peripheral surface of the portion 9 of the gear 7 and therefore will not in any way interfere with rotation of this gear for the period of time above stated.

20 It will also be understood that while the arrangement of gearing illustrated and described is a simple and convenient one for accomplishing the objects of the present invention, nevertheless any appropriate gearing may be employed capable of obtaining the same results, and it will also be evident that various modifications may be made in the construction and arrangement of parts so long as there is no departure from the spirit 25 of the invention.

25 In order to render the casing 1 sound proof, so that the sounds reproduced by the phonographic unit will not be audible to any one in the vicinity of the apparatus and thus conceal from the criminals the fact that a call 30 for help is being made, a lining 56 of felt or similar material is applied to the inner surfaces of the walls of the casing.

35 It will be understood of course that the casing 1 will be so located as to be completely concealed from view.

Having thus described the invention, what I claim is:

1. In alarm signalling apparatus, a telephonic transmitting circuit including a transmitter, a switch for closing said circuit, a phonographic unit including a rotatable record support, means for rotating the same, and a reproducer supported in cooperative relation to the record support and in communication with the telephonic transmitter, the record support rotating means including a gear having a continuously toothed peripheral portion and a peripherally smooth portion having a notch, an electromagnet, a

remote control switch in circuit with the magnet, an armature for the magnet having a tooth coacting with the notch of the last mentioned portion of said gear in the normal position of the gear and adapted to be 70 disengaged from the notch upon attraction of the armature through energization of the magnet, and means actuated through the rotation of said gear for effecting closing of said first mentioned switch for a predetermined period of time and a subsequent opening of said first mentioned switch, the said means comprising a gear in mesh with the first mentioned gear and a segmental pinion rotatable therewith, a segmental gear, a driving connection between said second gear and the segmental gear to rotate the segmental gear in a direction reverse to the rotation of said second gear, a rack bar connected with said first mentioned switch and having spaced 80 series of rack teeth for engagement by the teeth of the segmental pinion and the teeth of the segmental gear, said drive connection between the second mentioned gear and the last mentioned segmental gear providing for 85 engagement of the teeth of the segmental pinion with the rack to shift the rack in a direction to close said first mentioned switch, and a subsequent engagement of the teeth of the segmental gear with the other series 90 of teeth of the rack to effect return shifting of the rack to effect opening of said first mentioned switch.

2. In alarm signalling apparatus, a telephonic transmitting circuit including a transmitter, a switch arm, contacts in said circuit in circuit with the transmitter and engageable by the switch arm, a telephone set, contacts in circuit with said set and opposing the first mentioned contacts, the said 100 switch arm being movable between said sets of contacts, a phonographic unit including a rotatable record support, means for rotating the same, and a reproducer supported in cooperative relation to the record support and in communication with the telephonic transmitter, means for normally restraining the record support rotating means from operation, a remote control means for rendering the restraining means inactive, the restraining means for the record support rotating means including a gear, and means actuated through rotation of the gear to initially adjust the switch to close the circuit through the telephonic transmitter and, after a predetermined interval, adjust the switch to 105 close the circuit through the telephone set.

In testimony whereof I affix my signature.

CONRAD CHIERIGHINO.
